ROTATABLE WATER MANIFOLD FOR DISH WASHING MACHINES

John B. Tuthill, Kansas City, and William A. Claunch, Independence, Mo., assignors to American Dish Service of Kansas City, Missouri, Inc., Kansas City, Mo., a corporation of Missouri

Filed Oct. 6, 1967, Ser. No. 8,897

Term of patent 14 years

(Cl. D49—1)

Fig. 1.

Fig. 2.

Fig. 3.

Fig. 4.

Fig. 5.

Fig. 6.

FIG. 1 is a perspective view of the rotatable water manifold for dish washing machines, showing our new design;

FIG. 2 is a top plan view of the rotatable water manifold for dish washing machines;

FIG. 3 is a bottom view of the rotatable water manifold for dish washing machines;

FIG. 4 is a side elevational view of the rotatable water manifold for dish washing machines;

FIG. 5 is an end view thereof; and

FIG. 6 is an enlarged, cross-sectional view taken along line 6—6 of FIG. 4.

We claim:

The ornamental design for a rotatable water manifold for dish washing machines, as shown.
